UNITED STATES PATENT OFFICE.

ALBERT W. CROUCH, OF MILWAUKEE, WISCONSIN, ASSIGNOR TO MILWAUKEE YACHT & BOAT COMPANY, OF MILWAUKEE, WISCONSIN.

DESIGN FOR A BOAT.

44,998.

Specification for Design.

Patented Dec. 9, 1913.

Application filed April 30, 1913. Serial No. 764,692. Term of patent 7 years.

To all whom it may concern:

Be it known that I, ALBERT W. CROUCH, a citizen of the United States, residing at Milwaukee, county of Milwaukee, and State of Wisconsin, have invented a new, original, and ornamental Design for Boats, of which the following is a specification, reference being had to the accompanying drawing, forming a part thereof.

The drawing is a side elevation of a boat showing my new design.

I claim:

The ornamental design for a boat as shown.

ALBERT W. CROUCH.
